UNITED STATES PATENT OFFICE.

CHARLES H. MASON, OF CRANSTON, RHODE ISLAND, ASSIGNOR TO THEODORE W. FOSTER & BROTHER COMPANY, OF PROVIDENCE, RHODE ISLAND, A CORPORATION OF MAINE.

WATCH-HOLDER ATTACHMENT FOR BRACELETS.

1,071,250.

Specification of Letters Patent. Patented Aug. 26, 1913.

Application filed February 24, 1913. Serial No. 750,060.

To all whom it may concern:

Be it known that I, CHARLES H. MASON, a citizen of the United States, residing at Cranston, in the county of Providence and State of Rhode Island, have invented certain new and useful Improvements in Watch-Holder Attachments for Bracelets, of which the following is a specification.

My invention relates to devices adapted to be attached to bracelets of the expandible type, for holding watches, and it consists essentially in the novel construction of the holder itself, all as more fully hereinafter set forth and claimed.

15 The object of the invention is to provide a simple and comparatively inexpensive holder or container device adapted to readily receive and securely hold a watch therein.

20 The holder proper comprises a circular band of metal, concavo-convex transversely, capable of surrounding and snugly engaging the center rim of the watch; said band being separable and provided with means 25 for detachably securing or clamping it to the watch after the latter has been inserted therein; means being provided for adjusting the container to watch-rims varying slightly in circumference.

30 In the accompanying sheet of drawings, Figure 1 represents a front elevation of my improved watch-container attached to a flexible or link bracelet, as in use; Fig. 2 is a corresponding back elevation; Fig. 3 is a front view of the closed band or container itself (in enlarged scale) detached, the watch and bracelet members being omitted; Fig. 4 is a corresponding top plan view; Fig. 5 is a similar plan view, showing the adjacent ends of the members disconnected, ready to receive the watch in the container; and Fig. 6 is an inverted plan view, showing the lower portion of the container.

45 The following is a more detailed description of the invention, including the manner of its operation and use: The improved watch-holder or watch-container, as a whole, is indicated by the letter A. The holder

50 proper is annular (see Fig. 3) and comprises the two independent semi-circular sections a , a^1 , normally connected together at the top and bottom. The sections are formed from a relatively narrow, thin strip

55 or ribbon of suitable resilient metal and

bent to a semi-circular form longitudinally; the form transversely being preferably concavo-convex to conform to the center rim of the watch. A portion h of the edges of the lower part of the rim of the holder is 60 cut away, (see also Fig. 6) to freely receive the corresponding hinge-joints k of the watch-covers.

Bottom ears i are formed integral with the members a , a^1 , an adjusting screw s 65 passing longitudinally therethrough serves not only to snugly clamp the two halves of the holder A together, but at the same time allows for slight variations in the outer circumference of the center rim of watches. That is to say, there are some four standard or normal sizes of watches made; the cases of the watches in each of the respective sizes are liable, and, in fact, do vary slightly. Such variation may be provided for by 70 separating the juxtaposed faces of the ears i , as at j . Each section of the holder is provided with centrally arranged outwardly extending ears e adapted to receive the corresponding end member or link of a flexible bracelet, as B; pins or rivets w passing therethrough constituting a hinge joint and at the same time firmly securing the interposed holder in place against accidental loss.

75 The upper or free end portions b , b^1 of the main sections a , a^1 , respectively, are constructed to interlock when the device is normally closed. That is, the end portion b is enlarged in a lateral direction—see Figs. 90 5 and 6—and provided with a longitudinally extending open slot f^2 terminating in the central hole f adapted to receive the stem of the watch. The oppositely disposed or fellow end portion b^1 of the other main section a^1 is provided with laterally projecting hook-shaped lugs n , n , adapted to engage and interlock with correspondingly shaped registering notches m , m , formed in the inner opposite edges of said slot f^2 . The 95 extreme forward end of the part b^1 is cut away at f^1 and (when closed) forms the complement of said hole f of the other member.

100 In assembling and connecting the bracelet, watch and watch-container elements, the process is substantially as follows: The selected watch, as V, may be inserted in the container A when the latter is open, the stem t and head of the watch then extending 110

through the upper end of the container, after which its free or open end portions b, b^1 , are brought together, the sides of the opening j then engaging the stem t ; at the same time the act of closing the sections causes the end portion b^1 to ride up on the surface of the other end b until its lugs n register with the respective notches m , at which instant the part b^1 springs downward 10 into the slot j^2 and the lugs n into the notches, thereby securely locking the members together and inclosing the watch. If desired, the space j between the ears i may be further separated by retracting the screw s a suitable distance, followed by placing the watch in the container and interlocking the latter's notched end portions b, b^1 around the stem t , and by means of the screw s forcibly drawing the opposite ends i of the 15 container nearer together, thereby causing the sections a, a^1 to snugly engage the watch and at the same time to increase the holding tension upon the hook-shaped lugs n .

The length of the selected flexible bracelet proper B to which the watch-carrying holder is to be attached is such that the inner circumference of the bracelet plus the distance between the pins w , measured across the holder's face is equal to the normal length of a watchless bracelet of similar size. The two end links or members of the bracelet are adapted to be connected to the ears e of the respective members a, a^1 , by means of the joint pins or rivets w . 20 In lieu of first positioning the watch in the holder the latter may be made up and normally attached to the bracelet; later the selected watch may be readily mounted in the holder, first unclutching or unlocking 25 the latter for the purpose.

It is assumed that the bracelets are used in connection with ladies' watches, therefore, four normal sizes of watch-holders are employed, corresponding, respectively, with 30 the four standard sizes of watches.

I claim as my invention and desire to secure by United States Letters Patent:

1. As an improved article of manufacture, a watch-holder attachment device for flexible bracelets, said device consisting of a pair of oppositely disposed, substantially semi-annular main sections of metal for encircling a watch, said sections having a concavo-convex form transversely, manually

operable means for positively adjusting or varying the distance between the adjacent faces of the lower ends of the sections, the adjacent upper end portions of the sections being recessed to receive the stem of the watch, means integral with said upper end portions adapted, in cooperation with said adjusting means, for interlocking the closed sections against accidental opening or separation, and means integral with the sections, whereby the watch-holder is adapted to be attached to a bracelet.

2. In an article of the general class described, the combination of a pair of semi-circular main sections having a concavo-convex form transversely, means for adjustably connecting the two sections together at one end, means forming a catch for detachably interlocking the sections at the other or opposite end, and diametrically opposed hinge members integral with said sections adapted to be joined to a flexible bracelet.

3. A transversely separable annular holder, concavo-convex cross-sectionally, adapted to receive and hold a watch therein, said holder comprising a pair of inwardly facing sections, means for adjustably connecting the lower end portions of the holder together, whereby the lateral distance between the sections may be changed to accommodate watches varying in size, means co-operable with the upper end portions of the sections for detachably locking them together, and members fixed to the outer diametrically opposite edges of the holder adapted to be engaged by the end links of a bracelet.

4. An annular holder or container constructed to receive and support a watch, said holder comprising a pair of interlocking semi-circular sections joined together, means fixed to the holder for connecting the latter to the ends of an expansible bracelet, and having portions of its lateral edges cut away circumferentially to receive and seat 100 in said cut away portion the respective cover hinges of the watch.

In testimony whereof I have affixed my signature in presence of two witnesses.

CHARLES H. MASON.
